UNITED STATES PATENT OFFICE.

LEO BRAUN, OF MUNICH, GERMANY, ASSIGNOR TO PATENT MAILING SOUVENIR COMPANY, A CORPORATION OF NEW YORK.

SOUVENIR MAILING-CARD.

No. 806,631.

Specification of Letters Patent.

Patented Dec. 5, 1905.

Application filed May 29, 1903. Serial No. 159,317.

To all whom it may concern:

Be it known that I, LEO BRAUN, residing at Munich, in the Kingdom of Bavaria, in the German Empire, have invented a certain new and useful Souvenir Mailing-Card, of which the following is a specification.

The subject of my invention is a sheet or flat body of cardboard or other suitable material or combination of materials having a place for a mailing address and formed with a countersink, a depression, or a recess in which is located an album of views or photographs or the like and which is closed by a movable cover. The arrangement is preferably such that the address is provided for on one side and the souvenir feature on the other side, so that after the proper surface has been provided with an address the card is ready for mailing as printed matter.

One embodiment of the new device is shown in the accompanying drawings, in which—

Figure 1 is a plan, and Fig. 2 is a longitudinal section of the new article.

In carrying my invention into effect I take a sheet or flat object A of any suitable material, as above mentioned, and of any convenient size and thickness, and I provide such sheet with a depression, countersink, or recess α at any part, preferably in one face well within the perimeter of the card. Into this recess an album of views d is introduced and inclosed by a cover secured by a catch b or by other releasable means. The album is preferably secured to the cover, so that when the latter is opened the album is presented in convenient position for manipulation and examination. The cover is also preferably countersunk, so as to be flush with the surface of the card.

Having thus described my invention, the following is what I claim as new therein and desire to secure by Letters Patent—

1. A card provided with a recess, and a foldable device containing illustrations or the like, fitted in said recess and a movable cover for closing and opening the recess.

2. A souvenir mailing-card having on one side a place for an address, constructed with a recess and having combined with it, in said recess, an album of views.

3. A souvenir mailing-card having on one side a place for an address, constructed with a depression and having combined with it an album of views contained within the depre-

sion, and a movable cover to close the album 55 within the mailing-card.

4. A souvenir mailing-card having on one side a place for an address, constructed with a depression and having combined with it an album of views contained within said depression 60 and with a movable cover countersunk in said depression to close the album within the mailing-card.

5. A souvenir mailing-card having a side upon which to place an address, a flap or cover 65 of less dimension than the card on the side opposite the address side, and a series of pictures beneath the flap or cover and inlaid in the card.

6. A souvenir mailing-card having a side 70 upon which to place an address, a flap or cover of less dimension than the card, countersunk on and flush with the side opposite the address side, and a series of pictures beneath the flap or cover and inlaid in the card.

7. A souvenir mailing-card having a side 75 upon which to place an address, a flap or cover of less dimension than the card, countersunk on and flush with the side opposite the address side, and a series of pictures beneath the flap 80 or cover inlaid in the card, and releasable means for retaining the cover in closed position.

8. A souvenir mailing-card having a side 85 upon which to place an address, a flap or cover of less dimension than the card, countersunk on and flush with a side opposite the address side, and a series of pictures beneath the flap or cover and inlaid in the card; said cover being hinged at one edge to the card and having 90 a releasable catch engaging its other edge for holding the cover closed.

9. A mailing-card provided with a recess, and a foldable device containing illustrations or the like, fitted in said recess and a movable 95 cover for closing and opening the recess.

10. A mailing-card closed on one side and provided on its other side with a recess or depression, a movable closure for said recess or depression, and a foldable device adapted to 100 contain illustrations or the like, contained in said recess or depression.

11. A mailing-card closed on one side to provide a place for an address, and provided on its other side with a recess having immovable 105 or rigid walls, and a closure for the recess coextensive with the same and in its closed position flush with the recessed side of the card.

12. A mailing-card closed on one side to provide a place for an address, and provided on its other side with a recess having immovable or rigid walls, and a closure for the recess co-extensive with the same and in its closed position flush with the recessed side of the card and means for holding said cover in a locked position and permitting the same to be opened and locked again.
- 10 13. A mailing-card closed on one side to provide a place for an address, and provided on its other side with a recess having immovable

or rigid walls, and a closure for the recess co-extensive with the same and in its closed position flush with the recessed side of the card, 15 and an album of views positioned within said recess.

In testimony whereof I have signed this specification in the presence of two subscribing witnesses.

LEO BRAUN.
